(57) CLAIM

What is claimed is the ornamental design for mobius strip clothing, as shown and described.

DESCRIPTION

FIG. 1 is a front perspective view of a mobius strip clothing showing my new design;

FIG. 2 is a front perspective view thereof; and,
FIG. 3 is an enlarged detail view of a portion of mobius strip clothing of FIG. 1 taken from area 3 of FIG. 1, the undislosed portions are not part of the claimed design.

The broken lines are shown in the views for illustrative purposes only and form no part of the claimed invention.
